LOCKING PLATE ASSEMBLY AND TRANSMISSION

Filed Dec. 1, 1943

UNITED STATES PATENT OFFICE

2,442,763

LOCKING PLATE ASSEMBLY AND
TRANSMISSION

Morris Falk, Leominster, Mass., assignor to Independent Lock Company, Fitchburg, Mass., a corporation of Massachusetts

Application December 1, 1943, Serial No. 512,493

2 Claims. (Cl. 70—211)

1.

My present invention relates generally to door locks and more particularly to the locking plate assembly and transmission movement mechanism of bathroom locks or communicating door locks. Still more particularly my invention relates to door locks where a latch bolt is mounted for reciprocation, including a novel assembly of the locking plate and the transmission of movement from a lock operating mechanism to provide a compact construction.

In certain phases of my invention this application carries out in part some purpose of my application for door locks Serial No. 381,893, filed March 5, 1941, now Patent No. 2,370,645, granted March 6, 1945.

For purposes of explaining the general nature of my invention it may be pointed out that the present device is intended for use on a door of a bathroom or between communicating rooms, in which a latch bolt is retracted by a rotary spindle grasped by a door knob and in which the latch bolt is normally spring projected into the orifice of a strike plate mounted upon the frame of a door to hold the door in locked position, and in which, broadly speaking, the door knob spindle serves as a means for moving the latch bolt or the like and has a locking mechanism affecting the knob spindle to prevent oscillation of the knob spindle.

It is an object of my invention to provide a door lock including bolt retracting mechanism operable by a spindle of locking means and means for transmitting movement from a pin tumbler cylinder or the like to the locking means which will conveniently, economically and by compact arrangement make possible the application of the door lock mechanism of my application hereinbefore mentioned.

Still further objects of my invention reside in the provision of a locking plate assembly which may be inexpensively made and is of compact construction, whereby upon mounting beneath the escutcheon plate, compact and efficient spindle lock mechanism is provided, serving not only as a bathroom lock but as an inter-communicating door lock operable by pin tumbler cylinder mechanism.

For the attainment of the foregoing objects and such further objects as may appear herein or be hereinafter pointed out, I make reference to the accompanying drawing forming a part hereof, in which:

Figure 1 is a longitudinal sectional view showing my device;

Figure 2 is a face view of a detail taken in the

direction of the line 2—2 of Figure 1 with the locking mechanism in the locked position;

Figure 3 is a section taken on the line 3—3 of Figure 2;

5. Figure 4 is a view corresponding to that shown in Figure 2 of the mechanism in the unlocked position.

Making reference to the drawing, it is contemplated by my invention to provide a door 10 with a boring 11 within which there is positioned a latch casing 12 having a sliding bolt such as a latch bolt terminating in the edge of the door (not shown), arranged to project within an orifice in a strike plate. The latch bolt casing and mechanism for operating the same is illustratively shown in my application Serial No. 381,893 aforementioned. A transverse boring 13 intersecting the boring 11 is provided and through this there is passed a bolt or latch bolt operating spindle 14 entering the casing 12 and keyed to the bolt retractor mechanism in a manner well understood and more particularly illustrated in my application aforementioned.

Additionally, a transverse boring 15 is provided 25 to receive a rim lock 16 and rim lock operating spindle 17. With a construction thus provided, an exterior escutcheon plate 18 covers the borings 13 and 15. This escutcheon plate is formed with apertures 19 and 20 suitably flanged to receive the exterior door knob 21 and the rim 22 of the lock cylinder.

The interior face 23 of the door 10 is provided 35 with an interior escutcheon plate 24 having a flanged bearing orifice 25 to receive the interior spindle operating knob 26 in keyed position with the spindle 14. The upper portion of the escutcheon 24 is provided with a flanged bearing orifice 27 within which is rotatably mounted the lock actuating spindle 28. The interior end of 40 the lock operating spindle 28 is provided with a thumb operable knob or turn button 29.

Mounted within the escutcheon 24 there is provided a locking plate assembly 30, the details of which are more specifically shown in Figures 2, 3 45 and 4. The peripheral edges of the plate 30 are held within shoulders 31 formed in the escutcheon 24.

The plate 30 is formed with an orifice 31 within 50 which there is mounted the locking disc hub 32 operable by the knob spindle 14. An annular flange 33 passes through the orifice 31 and is upset at 34 over the washer 35 to hold the disc 32 rotatably mounted in position. The disc 32 is centrally formed with a keying orifice 36 55 to receive the spindle 14 in keying engagement.

The disc 32 has its periphery formed with a locking section 37 terminating into shoulder stops 38 and 39 arranged to engage the tongue 40 struck up from the body of the plate 30. The tongue 40 is arranged to lie in the path of the shoulders 38 and 39 and thereby limits the oscillating movement of the knob spindle 14 corresponding to the movement necessary to retract the bolt of the latch casing 12.

Positioned over the disc 32 I provide a locking cam 41 in tiltable position by passing a headed rivet 42 through an orifice 43 formed in the locking cam, the rivet being upset at 44 on the outer face of the plate 30. The rivet is formed with an enlarged head 45 beneath which is positioned the cam spring 46 in the form of a warped leaf spring having a finger 47 entering an orifice 48 to cause the cam spring 46 to move with the locking cam 41 as it is rotated in a manner which will appear more clearly as this description proceeds.

The cam spring 46 in its action beneath the head 45 of the rivet 42 holds the locking cam 41 in a predetermined position, offering adequate friction while permitting the tilting movement hereinafter to be described. The locking cam is formed adjacent its lower edge 49 with a disc engaging abutment corresponding substantially to the peripheral edge 37 of the locking disc 32. In position as shown in Figure 2 contact of the edges 37 and 49 will serve to prevent oscillation of the knob operated spindle 14.

Spacer pins 50 and 51 cooperate with pins 52 and 53 to maintain the plate 30 properly positioned in respect to the escutcheon plate 24 and adequately house the mechanism thus far described in relation to the escutcheon plate 24. These spacer pins may likewise be the shanks of rivets affixing the plate 30 to the escutcheon 24. The pins 50 and 51, however, act as abutments or stops for the locking cam 41. In the position shown in Figure 2 the pin 50 prevents counter-clockwise rotation of the locking cam 41 by engaging the edge 54 of the locking cam.

The locking cam 41 is sufficiently eccentrically positioned upon the rivet 42 to prevent displacement in oscillating the spindle 14. Thus, the pin 50, the eccentric position of the locking cam 41 coupled with the motion transmitting mechanism hereinafter described, all cooperate to prevent displacement of the cam 41 from its locking position, as in one direction of rotation of the disc 32 the cam will tend to be driven into abutting position with the pin 50, and in another direction of oscillation the eccentric mounting of the plate is in the pre-dead center position for any counter-clockwise movement which may be imparted to the locking disc 32.

The locking cam has its upper edge generally flared and is formed with the arcuate edge 55 whose center is coincident with the center through the rivet 42. This edge is formed with a segmented gear 56 arranged to mesh with the segmental gear 57 formed on the periphery of the turn knob spindle hub 58. The spindle hub 58 is formed with a flange 59 entering the orifice 60 in the plate and is then upset over the washer 61 to hold the hub 58 against displacement while revolvably mounted. Axially, the hub 58 is formed with a keying orifice 62 arranged to receive the lock operating spindle 28. The edge of the spindle 28 is slotted to receive in keying engagement the lock operating spindle bar 17 of ribbon contour.

While I have shown and described pins 50, 51, 75

52, and 53 as spacer pins, it will be understood that these pins may be integrally formed with the escutcheon plate 24 in a position corresponding to the orifices shown on the plate 30 at the pins 50, 51, 52, and 53, and that screws 63 may be passed through these orifices to engage the pins disposed from the escutcheon plate and properly support the plate in position with respect to the escutcheon to provide adequate clearance for the motion transmitting mechanism.

10 By the construction described and illustrated, it will be clear that oscillation of the interior knob 26 will carry with it the spindle 14 to retract the latch bolt mechanism within the casing 12.

15 In the position as shown in Figure 4, the locking disk 32 will be carried with the spindle 14, the action whereof being limited as the shoulders 38 and 39 come into contact with the tongue 40 upon counter-clockwise or clockwise oscillation. 20 The spindle carried by the turn button or knob 29 rotates the segmental gear 57 on the periphery of the turn knob spindle hub 58 to in turn transmit movement to the camming plate 41 until the limiting position is reached where the edge 54 25 abuts the pin 50. The camming edge 49 is then brought into engagement with the locking peripheral edge 37 on the locking disk 32, to prevent movement of the disk 32 thereby preventing retraction of the latch bolt through the medium of the spindle 14 passing through the keying opening 36.

30 While operation from the interior may be effected by the turn button or knob 29, similar locking and unlocking action may be secured by 35 the lock 16 operated by the key from the exterior and which may rotate the spindle bar 17 which in turn is keyed with the hub 58 carrying the segmental gear section 57.

36 Slight off position of the locking disk 32 from 40 the normal position caused by the inability of spring operation to overcome the bearing friction where a spring projected bolt is used or by a positively operated bolt, will be overcome by the resetting action provided by the interengagement 45 between the camming plate 41 and the locking disk 32 the operation of the device imparting oscillating movement to the locking cam 41 to restore it to the locking position. In this manner, not only does the locking cam serve to engage the peripheral edge 37 to hold the disk 32 50 against rotation, but movement is transmitted to it within limits tending to reset it to the normal position where the disk is in the position shown in Figures 2 and 4.

55 It will thus be observed that I have provided not only a novel spindle locking mechanism of compact and inexpensive construction, but a transmission for oscillating the bolt spindle from the turn knob or cylinder bar hub by the interengagement afforded by the plates comprising the camming plate and locking disk. Thus while my invention carries forth some of the features of my prior aforementioned application, for providing a bar lock construction, the transmission 60 assembly which I have provided readily adapts my construction for operation by a lock cylinder.

Having thus described my invention and illustrated its use, what I claim as new and desire to secure by Letters Patent, is:

70 1. In a door lock comprising a casing for a bolt and an oscillable spindle for operating the same to retract it, the combination therewith of a key operable plug and cylinder mounted on one side of the door and having a bar directed to the other side, an escutcheon covered plate on said last

side, a hub mounted on said plate into which said bar from said key plug extends in keying engagement, said plate carrying a transmission for oscillating said bolt spindle by movement of said first hub, said transmission including a pair of inter-engaging plates, each journalled on said first plate, one comprising a second hub to receive the bolt operating spindle in keying engagement, the other plate driven from said first hub, said inter-engaging plates being inter-related to permit oscillating the bolt spindle hub and having extended engaging peripheral portions to transmit rotary movement to the spindle hub from the first hub.

2. In a door lock in accordance with claim 1 wherein said transmission includes intermeshing segmental gears between said inter-engaging plates.
